United States Patent Office.

ANDREW GILBERT, OF BOSTON, MASSACHUSETTS.

Design No. 4,627, dated February 7, 1871.

DESIGN FOR TYPE.

The Schedule referred to in these Letters Patent and making part of the same.

I, ANDREW GILBERT, of the city of Boston, Suffolk county, and State of Massachusetts, have invented and produced a new Design for the Faces of Types, representing the letters, &c., of the English alphabet, of which the following is a specification.

In the drawings are seen the letters of two alphabets both of the same design generally, one representing the large capitals and the other the small capitals, also the numerals, &c.

My type-faces are of the style called, technically, the Gothic italic, and their forms vary from those of other types in that they are italic, and have but one broad or upright line, with no shading line; and, further, in that the right-hand "broad" (or upright) line in the letters A and H; also, the diagonal line in the letter R; also, the left-hand broad line in the letters M N AE, diphthong; also, the broad line in the letters F, J, P, and Y, and the straight line of the sign &;

also, the attachment which makes the letter O a Q; also, the ceriph of the letter G; also, in the numerals 3 4 5 7 9; also, the comma and the semicolon; also, in the small capitals, the broad line of the letter T, are continued down beyond the base line of the other letters and characters.

Further, the signs for a quotation mark, for an exclamation-mark, and for an interrogation mark, and in the numerals the numbers 6 and 8; also, the sign \$ and £ for dollars and pounds are continued above the line of the other letters and characters; and

What I claim herein as of my own invention, and desire to secure by Letters Patent, is—

The design of the said type, as described and shown.
ANDW. GILBERT.
